UNITED STATES PATENT OFFICE.

JOHN W. ELLIOTT, OF RUDD, IOWA.

SHEAF-CARRIER.

SPECIFICATION forming part of Letters Patent No. 284,400, dated September 4, 1883.
Application filed April 26, 1883. (No model.)

To all whom it may concern:

Be it known that I, JOHN W. ELLIOTT, a citizen of the United States of America, residing at Rudd, in the county of Floyd and State of Iowa, have invented certain new and useful Improvements in Sheaf-Carriers; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 This invention relates to a sheaf-carrying attachment for harvester-binders, its object being to collect the sheaves as discharged from the binder and drop them in heaps at convenient points for shocking, thus obviating the 20 labor and loss of time in gathering the sheaves singly. It has the further object to prevent imperfectly-bound gavels from being scattered as discharged from the binder.

The invention consists in the novel combination of devices, which will be hereinafter 25 particularly described with reference to the accompanying drawing, and definitely pointed out in the appended claim.

In the drawing is represented a perspective 30 view of a binder-frame with my improved sheaf-carrier connected thereto.

The letter A represents the binder-frame; a, the cross-beams supporting the platform b, on which is mounted the driver's seat C.

35 The letter D indicates the outer beam, which connects the sills E E. To this beam an outwardly-projecting horizontal arm, F, is secured by means of a clip, G, which embraces the beam and has its ends passed through the 40 arm F, as shown. This arm F projects from the front end of the binder-frame, and to its rear side is hinged a swinging slatted platform, H, composed of a head-piece, i, and a series of rearwardly-projecting fingers or slats, k, which at about midway their length are 45 connected to a common cross-piece, l, on their under sides.

To the under side of the head-piece i is secured one end of a diagonal brace, m, which 50 passes under the cross-piece l, and has its other end projecting inwardly beyond the inner fin-

ger or slat of the platform H. To the end of this diagonal brace m is secured one end of a cord, N, which passes upward over a pulley, o, mounted on one of the cross-beams a a, 55 thence over a pulley, o', mounted on a standard, s, and from this pulley to a lever, P, having one end pivoted to one of the posts of the binder-frame, and the other end extended inwardly to within reach of the driver when 60 upon his seat, the free end of said lever being also within reach of the driver when it stands vertically against the standard s.

Projecting from the cross-beam a is a standard, Q, provided with its shoulder q, arranged 65 to engage the lever P and hold it in a horizontal position, the rear edge of said standard above the shoulder being beveled to form a guide for the lever in its downward movement. A finger-spring, r, stands alongside 70 the standard Q, and serves to prevent the lever P from being jolted out from under the shoulder q.

The letter T indicates the discharge-platform over which the sheaves pass as discharged 75 from the binder. I have not deemed it necessary to show the binding mechanism in the drawing, as my sheaf-carrier may be used to receive the sheaves from any of the ordinary styles of binders.

80 The operation of the invention is as follows: When the harvester is traveling in the field, the sheaf-carrier H stands normally in the position as shown in the drawing and receives sheaves as discharged successively from the 85 binder until a proper number has been collected. In order to drop the sheaves, the driver seizes the lever P and moves it slightly laterally, so as to disengage from the shoulder q and allow it to rise, so that the cord N will run 90 over the pulleys and allow the sheaf-carrier H to swing downward and discharge the collected sheaves in a heap convenient for shocking. The outer finger of the sheaf-carrier is provided with a guard, h', to prevent the 95 sheaves from rolling off the outer edge of the carrier.

It frequently happens that sheaves are imperfectly bound and the straw is scattered when such sheaves are discharged singly onto 100 the field; but it is one of the advantages of my improvement that it will carry the straw

of such sheaves and drop it with the others in convenient position to be bound by hand by the shockers. The main advantage of the invention is, however, that it obviates the necessity for the great expenditure of time and labor heretofore required in collecting the sheaves one by one from the field and carrying them to points where they are to be formed into shocks.

10 Having now fully described my invention, what I claim as new, and desire to secure by Letters Patent, is—

The sheaf-carrying attachment consisting of the arm F, provided with a clip, G, the sheaf-

carrying platform H, composed of the fingers 15 or slats, and the head-piece hinged to the horizontal arm, and diagonal brace attached at one end to said head-piece, and having its other end projecting inwardly to the inner finger or slat of the platform, and guard h', attached to 20 the outer finger of the platform, substantially as described.

In testimony whereof I affix my signature in presence of two witnesses.

JOHN W. ELLIOTT.
